WRENCH FOR INSERTING OR REMOVING PIPE UNION NIPPLES

George Brase, San Francisco, Calif., assignor of twenty percent to Alice F. Jones, San Francisco, Calif.

Filed Aug. 24, 1959, Ser. No. 835,542

3 Claims. (Cl. 81—53)

The present invention relates to plumbers' tools, and particularly to one for manipulating—i.e. for installing or removing—the male nipple of a pipe union. Such nipple is the part of the union having the rounded machine-finished nose thereon, and it is difficult to mount or remove such nipple from the tapped member intended to receive it, such—for instance—as a steam-heating radiator; the other part of the union being incorporated in this case in the steam-control valve for the radiator. Attempts have been made to simplify such manipulation by providing the nipple with internal lugs adapted for tool engagement, but these lugs tend to choke the flow through the nipple, and—being necessarily small—frequently snap off when nipple-turning pressure is applied thereto.

The principal object of this invention is to eliminate the need of such lugs by the provision of a wrench by means of which the union nipple may be engaged and turned in either direction—so as to screw or unscrew the nipple relative to the member tapped to receive the nipple—with-out danger of marring the finish on the rounded nose of said nipple, in a quick and easy manner.

It is also an object of the invention to provide a pipe union nipple wrench which is designed for ease and economy of manufacture.

Still another object of the invention is to provide a practical and reliable pipe union nipple wrench, and one which will be exceedingly effective for the purpose for which it is designed.

These objects are accomplished by means of such structure and relative arrangement of parts as will fully appear by a perusal of the following specification and claims.

In the drawings:

Fig. 1 is a side elevation of my improved wrench with the two members thereof separated, and one member broken out at one end and in section.

Fig. 2 is a side elevation of a union nipple and nut as installed in a radiator, and engaged by one member of the wrench; the latter and the nut being in section.

Fig. 3 is a similar view, but showing the complete wrench as applied to the nipple for the purpose of installing or removing the same from the radiator body.

Referring now more particularly to the drawings, and to the characters of reference marked thereon, the union nipple 1, for which my improved wrench is designed, includes a pipe-threaded portion 2 on one end adapted to be screwed into a tapped hole in a radiator 3 or the like, and a rounded or tapering machined nose 4 on the other or outer end, with an enlarged annular flange 5 at the base of the nose. The nipple includes the usual machine-threaded nut 6 turnably embracing the same in overhanging relation to the nose 4, and having a flange 7 behind and engaging the flange 5. The nut cannot therefore be removed from the nipple as long as the latter is mounted in the radiator 3.

The wrench to engage such nipple 1 comprises a pair of separate but cooperating members, indicated generally at 8 and 9. Member 8 is a tubular body which at one

2

end is right-hand threaded for a certain length, as at 10, for threaded engagement with the nut 6, as shown in Fig. 2. Back of the threaded portion said member is formed as a rectangular or hexagonal head 11 for conventional wrench engagement.

Internally, at its threaded end, member 8 is formed with a circumferential seat 12 to fit over the nose, while leaving the outer end portion of the same exposed, as shown in Fig. 2. The inner end of the seat merges into a straight bore 13 which extends for a short distance and is followed by left-hand machine threads 14 which extend to the opposite end of the member 8; the diameter of the threads 14 at their tips being no less than that of the bore 13, as shown.

Member 9 is a substantially solid body which at one end is formed as a smooth neck 15 of a size to fit within bore 13 of member 8. The outer end of the neck is provided with a seat 16 curved to engage the nipple nose 4 back from the portion thereof engaged by seat 12, as shown in Fig. 3.

The end of member 9 opposite the neck 15 is formed as a rectangular or hexagonal head 17, preferably the same size as head 11 of member 8, and between such head 17 and the neck 15 said member 9 is formed with left-hand machine threads 18 to engage the tapped threads 14 of member 8.

In operation, to mount the nipple 1 in radiator 3, member 8 is engaged with said nipple so that the nose 4 of the nipple enters the member 8 and engages the seat 12. The nut 6 is then advanced and its threads engaged with threads 10 of member 8, so that the nut and member 8 are both held in tight clamping relationship with the flange 5 and nose 4, respectively, of the nipple 1, as shown in Fig. 2.

Member 9 is then advanced into member 8, upon left-hand turning of said member 9, until seat 16 thereof tightly engages the outer end portion of the nose 4, as shown in Fig. 3. To mount the nipple in the radiator 3 an ordinary wrench is then applied to head 11 to turn said member 8 and the nipple onto radiator 3. With such rotation, any tendency of member 8 to slip and turn on the nose 4 is counteracted and prevented by the tendency of the member 9 to rotate in the opposite direction—due to the left-hand threading thereof—and thus cause the seat 16 to more tightly clamp onto the nose 4.

To remove the nipple from the radiator 3 an ordinary wrench is applied to the head 17 of member 9 to turn the same in a left-hand or anti-clockwise direction. Such turning of course tends to further advance the member 9 into member 8 to cause the seat 16 to more tightly grip the nose 4.

When the nipple is mounted or removed, it is only necessary to loosen member 9 and unscrew the nut 5.

From the foregoing description it will be readily seen that there has been produced such a device as will substantially fulfill the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A wrench for inserting and removing a male pipe-union nipple having a sloping-sided nose, an enlarged flange at the base of the nose, and a nut overhanging the nose and having an inturned flange at its back end to engage the nose flange and limit advance of the nut; the wrench comprising a tubular open-ended member

threaded on the outside at one end for engagement by the nut and provided at said end with an internal seat shaped to match and fit on the nose and at the other end being tapped with threads cut in the direction opposite those on the outside, said member back of said outside threads being adapted for other wrench engagement, and another member having a body externally threaded intermediate its ends to engage the tapped threads on the one member, one end of said other member being adapted for other wrench engagement and the other end being arranged for engagement with the end of the nipple nose.

2. A wrench for inserting and removing a male pipe-union nipple having a sloping-sided nose, an enlarged flange at the base of the nose, and a nut overhanging the nose and having an inturned flange at its back end to engage the nose flange and limit advance of the nut; the wrench comprising a tubular open-ended member threaded on the outside at one end for engagement by the nut and provided at said end with an internal seat shaped to match and fit on the nose while leaving the other end portion thereof exposed beyond the seat, said member at the other end being tapped with threads cut in the opposite direction to those on the outside, said member beyond the external threads being adapted for other wrench engagement; another member comprising a body externally threaded intermediate its ends to engage the tapped threads in said one member, the outer end of the body being adapted for other wrench engagement, and a neck on the inner end of the body of a size to project through said one member to the seat thereof and having a circumferential seat in the end of the neck arranged to fit and engage over said exposed portion of the nose.

5
10

3. A wrench for inserting and removing a male pipe-union nipple having a sloping-sided nose, an enlarged flange at the base of the nose, and a nut overhanging the nose and having an inturned flange at its back end to engage the nose flange and limit advance of the nut; the wrench comprising a member adapted on the outside for other wrench engagement and having means for engagement with the nut and with the nose on the outside to clamp the two together, and another member cooperating with the first member in clamping relation therewith and with the nose of the nipple, and adapted on the outside for other wrench engagement; the first named wrench being arranged so that the nipple will be rotated with the first named wrench as a unit in one direction upon other wrench engagement and rotation of one member, and so that the nipple will be rotated with the first named wrench as a unit in the opposite direction upon other wrench engagement and rotation of the other member.
